ELECTRIC CURRENT RECTIFIER

Filed June 18, 1932

UNITED STATES PATENT OFFICE

1,989,464

ELECTRIC CURRENT RECTIFIER

Samuel Ruben, New Rochelle, N. Y., assignor to
 Ruben Rectifier Corporation, Englewood, N. J.,
 a corporation of Delaware

Application June 18, 1932, Serial No. 617,960

23 Claims. (Cl. 175—366)

This invention relates to electric current rectifiers and the like which employ asymmetric couples of the dry surface contact variety and, more particularly, to such couples including one electrode element of a relatively electropositive material and another electrode element of a relatively electronegative material adapted to cooperate with the former for the electrochemical formation and maintenance at their junction of an inverse current-blocking film.

General objects of the invention are the provisions of such a device having improved characteristics and which is efficient, economical and readily manufactured; an electropositive electrode element thereof having improved electrical characteristics; and structural embodiments of the device which are readily constructed and allow efficient use and operation of the device.

A more specific object of the invention is the provision of such a device wherein the electropositive electrode element of a silicon material has a high contact resistance with the electronegative electrode element which includes a surface, preferably of a compound of an element chosen from an empirical group of elements of sub-group B of Mendelejeff's periodic table of elements, to provide in the device a contact resistance sufficient to maintain an inverse current-blocking film at the contacting surfaces resulting in a substantially equal distribution of the current over the entire area, and to obtain chemical stability, reduction of the resistance of the electronegative element and the amount of current necessary to form and maintain the inverse current-blocking film at the junction of the electrode elements, steadiness of output, and increased efficiency.

Another object of the invention is the provision of a simple and cheap structure including a metallic base member provided with a projecting portion having a surface of an electronegative electrode compound which cooperates with a mass of a silicon material held in position thereagainst by an insulated cup wall and a projecting portion on a resilient member, the latter being secured to the base by suitable means adapted to exert sufficient pressure on the units for efficient surface contact and operation.

A further object of the invention is the provision of a special structure whereby if desired the units of the asymmetric couple may be operated in a vacuum.

Other objects of the invention will in part be obvious and will in part appear hereinafter.

The invention accordingly comprises the fea-

tures of construction combination of elements, and arrangement of parts, which will be exemplified in the constructions hereinafter set forth and the scope of the application of which will be indicated in the claims.

Fig. 1 is a top view of one form of the device of the present invention;

Fig. 2 is a sectional view on line 2—2 of Fig. 1;

Fig. 3 is a bottom view of the device depicted in Figs. 1 and 2;

Fig. 4 is a sectional view of a modification of the device depicted in Figs. 1 and 2;

Fig. 5 is a view partly in section and partly in elevation of a modification of the device of the present invention; and

Fig. 6 is an elevational view of another modification of the device of the present invention, with parts broken away.

Prior to the present invention electrical current rectifiers and the like which employed asymmetric couples of the dry surface-contact variety comprising a relatively electropositive electrode element and a relatively electronegative electrode element adapted to cooperate with the former for the electrochemical formation and maintenance at their junction of an inverse current-blocking film have been provided with a contact resistance to perform such functions by the oxidation of the surfaces of the electropositive electrode element, the interposition between the electrode elements of a resistance layer of a film-forming material, or by the addition of resistance coatings to the electronegative electrode element. Such units have been frequently characterized by non-uniform operating characteristics and instability during operation under ordinary atmospheric conditions. These undesirable characteristics of the prior art devices are substantially eliminated by the present invention.

In accordance with the present invention a device of this type is provided which has an electropositive electrode element formed from a silicon material, that is, silicon alone or a compound of silicon and an element chosen from an empirical group of more electropositive elements of the electrochemical table of elements preferably chosen from the second and third periodic groups of Mendelejeff's periodic table of elements, such as, for example, beryllium, magnesium, calcium, zinc and aluminum. This electropositive electrode element is placed in surface contact with an electronegative electrode element having a high contact resistance with the electropositive electrode element and is preferably formed from, or provided with a surface of, a

- compound of an element chosen from an empirical group of elements of sub-group B of the sixth periodic group in Mendelejeff's periodic table of elements such as, for example, sulphur, 5 selenium and tellurium. The other constituents of the compound forming the electronegative material may be any suitable metal or alloy thereof chosen from an empirical group of metals or materials, such as, for example, copper, silver, 10 brass, etc. Sufficient pressure is applied to the electrode elements to insure good contact between their adjacent surfaces and an inverse current-blocking film is formed at the junction of the elements by allowing current to flow therethrough 15 during the forming period. The high contact resistance of the electropositive electrode element with the electronegative electrode element maintains this inverse current-blocking film during 20 operation of the device.
- 20 It has been found that silicon alone may be used for the electropositive electrode material but since its internal resistance is relatively high a compound of silicon and a more electropositive material which has a lower specific resistance, 25 such as magnesium, is preferred. The resulting compound has a lower specific resistance than that of silicon its use thus being attended by a smaller I^2R loss and it has a sufficient internal resistance to obtain with the electronegative material the desired relatively high contact resistance to cause the formation of the inverse current-blocking film when current is passed between the electropositive electrode material and the electronegative electrode material.
- 30 Silicon and silicide compounds have an additional advantage over magnesium, or compounds thereof other than magnesium silicide, in that they are chemically stable and can be operated under ordinary atmospheric conditions and without external chemical effects, such as oxidation, 35 and consequent inefficiencies in operation.
- Referring to the drawing, Figs. 1 and 2 show views of one form of the device of the present invention which consists of a metallic base member 45 10 of any good electrically conductive material, copper being preferred, provided with a substantially cylindrical plug 11 of electrically conductive material such as copper. If desired, this plug member 11 may be made integral with the base 50 member 10. One face of the plug member 11 is provided with a layer 12 of a relatively electronegative material, such as, copper sulphide, which may be directly formed thereon by subjecting the 55 face of the plug 11 to the action of sulphur vapors in a well known manner or may be formed by placing on the face of the plug member 11 a mass of granular copper sulphide the particles preferably being of a size which pass through a screen of between about 36 mesh and 60 mesh.
- 60 An insulating collar 13 is positioned over the sulphide plug 11 to form a cup member having insulating walls 14 and a bottom of a relatively electronegative material. The collar 13 may be formed from any suitable insulating material but 65 to prevent fracture thereof when pressure is applied to the unit is preferably formed from aluminum and coated on the inside with an insulating oxide layer. A mass 15 of a relatively electropositive material, such as a silicon material, magnesium silicide being preferred, is positioned within the collar 13. This mass 15 may 70 consist of a single crystalline structure or of several small pieces of the silicide compound.
- 75 A resilient metallic member 16, preferably in the form shown to include a plurality of resilient

arms 17, is provided with a substantially cylindrical projecting portion 18, preferably of copper, adapted to project into the collar 13 and contact the mass 15. Each of the arms 17 is apertured to receive a bolt 19 of sufficient length to extend through an aperture in the base member 10, the bolt 19 being insulated from the base member 10 by an insulating collar 20. These bolts are adapted to hold the assembly together in a manner depicted in Fig. 2 to stress the resilient 10 arms 17 and thus apply a sufficient pressure to the mass 15 between the plug member 11 and projecting portion 18 to insure good contact therebetween. This device is completed by securing to the base member 10 an electrical terminal 21 and mounting an additional electrical terminal 22 in electrical contact with the resilient member 16 in any desired manner.

In Fig. 4 is shown a modification of the structure depicted in Figs. 1 and 2. The base member 10', similar to the base member 10 of Fig. 2, is preferably formed from copper and integral with the plug or projecting portion 11' and is provided with a threaded shank 23. The projecting portion 11' is provided with the surface 12 of electronegative material and the collar 13 is positioned thereover and the mass 15 of silicon material is placed therein. Another base member 10'' having a projecting portion 11'' and a threaded shank 23' is positioned as shown with 25 the face of the projecting portion 11'' in contact with the mass 15 within the collar 13. A resilient spider 24, shaped in plan view similarly to the member 16 but with the arms thereof bowed as shown, is positioned over the shank 23', and the 30 bolts 19', extending through holes in the spider 24 and base members 10', 10'', complete the assembly. These units may be arranged in series by coupling together shanks 23 and 23' of adjacent 35 units with internally threaded collars 25.

In Fig. 5 is shown a modification of the device wherein several asymmetric couples similar to the one depicted in Figs. 1 and 2 are arranged in series. Each of the base members 26 is formed similarly to that of member 16, each being provided, however, with a plug 27 similar to plug 11 mounted on the base member 10. Each of these plug members 24 dually perform the functions of the members 11 and 18 of the device depicted in Figs. 1 and 2 when the units of the present 45 modification are stacked as shown with masses 15 interposed between the adjacent plug members and confined within the insulating collars 13. Through bolts 28 secure the units of the assembly 50 together, insulating collars 29 being used to prevent shorting of the couples, and electrical terminal members 21 and 22, each in electrical contact with an end unit, as in the first modification, 55 complete the assembly.

When desired, the asymmetric couple or couples may be mounted and operated in a vacuum through the use of a suitable structure, such as that shown in Fig. 6 which comprises a vacuum tube base 30 provided with terminal member supports 31 suitably secured to terminal members 32, preferably of copper. A pair of electrode elements 33 and 34 are interposed between adjacent terminal members 32-32. These units are secured together by a bolt 35 insulated from the units by a suitable insulating sleeve 36. The 60 device shown in Fig. 6 is a double wave rectifying device, each half-wave of the alternating current being rectified by one pair of electrode elements 33 and 34. In such case the two electrode elements 33-33 are preferably formed from a 65 70 75 80 85 90 95

pressed mass of silicide compound, such as, magnesium silicide or calcium silicide. The electrode elements 34-34 are preferably formed from copper sulphide.

5 In operation of the device depicted, the silicon material electrode element forms the cathode and the copper sulphide electrode element forms the anode and when a current is passed between these electrode elements during the 10 forming period an inverse current-blocking film is formed therebetween. It is believed but it is by no means certain that this current-blocking film, when the anode is formed from copper sulphide and the cathode is formed from magnesium silicide, is sulphides of silicon and magnesium. I 15 do not wish, however, to be bound by this theory with regard to the probable nature of the compound forming the inverse current-blocking film.

It will thus be seen that the present invention 20 efficiently attains the objects set forth above and provides asymmetric couples which are simple and rugged in structure and efficient in operation, units including an electropositive electrode element of a silicide of magnesium and an electronegative electrode element of a sulphide of copper having been operated at an efficiency of as high as 80 per cent. The particular structures set forth provide simple means for the utilization 25 of masses of a silicon material for the electropositive electrode element while maintaining efficient contact between this element and the electronegative electrode element. Such structures also allow a considerable reduction in the amount 30 of electronegative material and a consequent reduction of the resistance of the electronegative material, a very thin layer thereof being all that is necessary for efficient operation.

The use of the expression, "in electric current rectifiers and the like, an asymmetric couple" is 40 intended to cover devices which have the property of conducting current in one direction and blocking current in the reverse direction.

Since certain changes may be made in the above constructions and different embodiments 45 of the invention could be made without departing from the scope thereof, it is intended that all matter contained in the above description or shown in the accompanying drawing shall be interpreted as illustrative and not in a limiting 50 sense.

It is also to be understood that the following 55 claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. A unilateral conductive electric couple comprising a body of a silicon material maintained 60 in contact with a body of relatively electronegative material, said silicon material having a high contact resistance with said electronegative material and cooperating therewith for the electro-thermal formation and maintenance at their junction of reactionary products formed between elements of the electropositive and electronegative materials to act as an inverse current-blocking film, said silicon material comprising at least 65 one of the materials silicon and silicides of elements constituting an empirical group of elements of the second and third periodic groups in Mendelejeff's periodic table of elements.

2. A unilateral conductive electric couple comprising a body of a silicon material maintained 70

in contact with a body of relatively electronegative material, said silicon material comprising a compound of silicon and an electropositive element chosen from an empirical group of more electropositive elements of the electrochemical table of elements, and having a high contact resistance with said electronegative material and cooperating therewith for the electro-thermal formation and maintenance at their junction of reactionary products formed between elements of the electropositive and electronegative materials to act as an inverse current-blocking film, said electronegative material including at least one electronegative compound chosen from an empirical group comprising sulphides, selenides and tellurides. 15

3. A unilateral conductive electric couple comprising a body of a silicon material maintained in contact with a body of relatively electronegative material, said silicon material comprising a silicide compound of an element chosen from an empirical group of elements of the second and third periodic groups in Mendelejeff's periodic table of elements and having a high contact resistance with said electronegative material and 20 cooperating therewith for the electro-thermal formation and maintenance at their junction of reactionary products formed between elements of the electropositive and electronegative materials to act as an inverse current-blocking film, said 25 electronegative material including at least one electronegative compound chosen from an empirical group comprising sulphides, selenides and tellurides. 30

4. A unilateral conductive electric couple comprising a body of a silicon material maintained in contact with a body of relatively electronegative material, said silicon material comprising a silicide compound of an element chosen from an empirical group of elements including beryllium, 40 magnesium, calcium, zinc and aluminum, and having a high contact resistance with said electronegative material and cooperating therewith for the electro-thermal formation and maintenance at their junction of reactionary products 45 formed between elements of the electropositive and electronegative materials to act as an inverse current-blocking film, said electronegative material including at least one electronegative compound chosen from an empirical group comprising sulphides, selenides and tellurides. 50

5. In electric current rectifiers and the like, of the dry surface-contact variety, an asymmetric couple comprising a relatively electropositive electrode element of a silicon material, and a relatively electronegative electrode formed from one of the three general groups of materials, sulphides, selenides and tellurides in surface contact with said electropositive electrode. 55

6. In electric current rectifiers and the like, of the dry surface-contact variety, an asymmetric couple comprising a relatively electropositive electrode element of a silicide compound of one of the elements of the second and third periodic groups in Mendelejeff's periodic table of elements, and a relatively electronegative electrode element having a surface of an electronegative compound including an element chosen from an empirical group of elements of sub-group B of the sixth periodic group in Mendelejeff's periodic table of elements in surface contact with said electropositive electrode. 65

7. In electric current rectifiers and the like, of the dry surface-contact variety, an asymmetric couple comprising a relatively electropositive 70

- electrode element of a silicide compound of an element chosen from an empirical group of elements including beryllium, magnesium, calcium, zinc and aluminum, and a relatively electronegative electrode element having a surface of electronegative material of at least one compound chosen from an empirical group comprising sulphides, selenides, and tellurides in surface contact with said electropositive electrode.
10. 8. In electric current rectifiers and the like, of the dry surface-contact variety, a relatively electropositive electrode element of a silicide compound of one of the elements magnesium and calcium and a relatively electronegative electrode element of a sulphide of copper in surface contact with said electropositive electrode.
15. 9. A unilateral conductive couple comprising a body of a silicide of magnesium maintained in contact with a sulphide of copper.
20. 10. A unilateral conductive couple of the dry surface-contact variety comprising a metallic base member, a projecting portion thereon having a face of a relatively electronegative compound, an insulating collar positioned over said projecting portion, a mass of a relatively electropositive compound in said collar in contact with the electronegative compound, a resilient metallic member having a portion projecting into said collar and contacting said mass, and means to secure said resilient member to said base and apply pressure to said mass.
25. 11. A unilateral conductive couple of the dry surface-contact variety comprising a metallic base member, a projecting portion thereon including a cup-shaped member provided with insulating side walls and a bottom of a relatively electronegative compound including an element chosen from an empirical group of elements of sub-group B of the sixth periodic group in Mendelejeff's periodic table of elements, a mass of a silicon material disposed in said cup-shaped member, another metallic base member having a metallic projecting portion engaging said mass, and means to secure said base members together 30 in an insulated manner and to apply pressure to said mass.
30. 12. A unilateral conductive couple of the dry surface-contact variety, comprising a metallic base member, a projecting portion of copper thereon the face of which consists of a compound of copper and an element chosen from an empirical group of elements including sulphur, selenium and tellurium, an insulating collar positioned over said projecting portion, a mass of a silicon material disposed in said collar in contact with the copper compound, a resilient metallic member having a portion projecting into said collar and contacting said mass, and means extending between said base and said resilient member to 35 secure the units of the assembly together and apply pressure to said mass.
35. 13. In electric current rectifiers and the like, an asymmetric couple comprising a vacuum tube base, spaced apart terminal members supported substantially vertically on said base, a relatively electropositive electrode element of a silicide compound of one of the elements of the second and third periodic groups in Mendelejeff's periodic table of elements and a relatively electronegative electrode element of a relatively electronegative compound including an element chosen from an empirical group of elements of sub-group B of the sixth periodic group in Mendelejeff's periodic table of elements in surface contact with each other positioned between said terminal members,
40. transverse means to hold said terminal members in surface contact with said electrodes and the latter in surface-contact with each other, and an evacuated envelope mounted on said base and enclosing said terminal members and electrodes. 5
45. 14. In electric current rectifiers and the like, an asymmetric couple comprising a vacuum tube base, spaced apart metallic terminal members supported on said base, a relatively electropositive electrode element of a silicon material in contact with one of said terminal members, a relatively electronegative electrode element of electronegative material of at least one compound chosen from an empirical group comprising sulphides, selenides and tellurides in contact with the other of said terminal members and said electropositive electrode element, a member transfixing said terminal members and said electrode elements adapted to hold said units in contact with each other and insulated therefrom, 20 and an evacuated envelope mounted on said base and inclosing said units. 15
50. 15. In electric current rectifiers and the like, the combination comprising a vacuum tube base having at least three terminal prongs, at least three substantially aligned spaced apart terminal members of electrically conductive material supported on said base each being electrically connected to one of said prongs, two pairs of electrode elements interposed between adjacent terminal members each of said pair of elements including a relatively electropositive electrode element of a silicon material and a relatively electronegative electrode element of a relatively electronegative compound including an element chosen from an empirical group of elements of sub-group B of the sixth periodic group in Mendelejeff's periodic table of elements, a bolt transfixing all of said terminal members and electrode elements and insulated from said units, and an evacuated envelope mounted on said base and inclosing said units. 30 35
55. 16. A unilateral conductive electric couple comprising an electropositive electrode formed from silicon and one of the elements beryllium, magnesium, calcium, zinc and aluminum maintained in contact with an electronegative electrode formed from one of the three general groups of materials, sulphides, selenides and tellurides. 40 45
60. 17. A unilateral conductive electric couple comprising an electropositive electrode formed from silicon and magnesium maintained in contact with an electronegative electrode formed from one of the three general groups of materials, sulphides, selenides and tellurides. 50 55
65. 18. A unilateral conductive electric couple comprising an electropositive electrode formed from silicon and aluminum maintained in contact with an electronegative electrode formed from one of the three general groups of materials, sulphides, selenides and tellurides. 60
70. 19. A unilateral conductive electric couple comprising an electropositive electrode formed from silicon and calcium maintained in contact with an electronegative electrode formed from one of the three general groups of materials, sulphides, selenides and tellurides. 65
75. 20. A unilateral conductive electric couple comprising an electropositive electrode formed from silicon and one of the elements beryllium, magnesium, calcium, zinc and aluminum maintained in contact with an electronegative electrode formed from a compound of one of the elements sulphur, selenium and tellurium with copper. 70 75

21. A unilateral conductive electric couple comprising an electropositive electrode formed from silicon and one of the elements beryllium, magnesium, calcium, zinc and aluminum maintained in contact with an electronegative electrode formed from copper sulphide.
22. A unilateral conductive electric couple comprising an electropositive electrode formed from silicon and one of the elements beryllium, magnesium, calcium, zinc and aluminum maintained in contact with an electronegative electrode formed from brass sulphide.
23. A unilateral conductive electric couple comprising an electropositive electrode formed from silicon and magnesium maintained in contact with an electro-negative electrode formed from copper and sulphur.
